UNITED STATES PATENT OFFICE.

WILLIAM REED-LETHBRIDGE, OF WELLINGTON, NEW ZEALAND.

ILLUMINATED SIGN.

1,274,907.

Specification of Letters Patent.

Patented Aug. 6, 1918.

Application filed June 23, 1915. Serial No. 35,914.

To all whom it may concern:

Be it known that I, WILLIAM REED-LETHBRIDGE, subject of the King of Great Britain and Ireland, residing at Number 10 Hawker street, in the city of Wellington, in the Dominion of New Zealand, have invented a new and useful Improvement in Illuminated Signs; and I do hereby declare the following to be a full, clear, and exact description 10 of the same.

This invention relates to illuminated signs of the class wherein an intermittent illumination is employed to display the matter.

The invention has for its object the obtaining in an effective manner a change of matter upon one or more stationary plates or sheets by means of intermittent illumination.

According hereto a plate or sheet of material which when illuminated by a light of greater magnitude from the rear than from the front will render any matter depicted on the front thereof invisible, but any matter depicted upon the rear thereof and illuminated from behind will be visible through it, is provided within a suitable casing.

In order to obtain this effect the material employed must be interstitial and the interstices of such a nature that a coating of paint or the like medium will not close them up and so prevent the light passing through them, but such that varnish or other such like transparent substance will fill up the interstices.

A suitable material is wire gauze or finely perforated metal. Throughout the specification and claims where an interstitial or perforated material is mentioned a material that will give the above result will be understood.

The intermittent illumination of the different sheets may be brought about by an ordinary electric flasher or modification thereof.

Where both lights are intermittent the flasher will switch one set of lights off synchronously with switching the other set on.

In the accompanying drawings

Figure 1 is a front elevation of the sign.

Fig. 2 is a cross sectional elevation on line A—A Fig. 1.

Fig. 3 is a front view of the sheet of interstitial material.

Fig. 4 is a cross section of the said sheet.

Fig. 5 is an enlarged view of a portion of 55 the material.

Referring to the drawings the sheet of interstitial material 1 is provided in a casing 2 having an open front. The said sheet 1 is stretched upon a frame 3 which is guided 60 and retained in position by means of a recess 4 in the bottom and sides of the casing 2. The top of the casing 2 has a slot 5 opposite the recess 4 through which the frame 3 is passed.

By this means sheets having different display matter upon them may be easily substituted for the sheet that is being employed.

The sheet of interstitial matter consists of a substance of which the material itself is 70 opaque or may be rendered opaque and the interstices of which are of the same or greater area than the material itself. So far I have found wire gauze of fine mesh the most suitable for this purpose.

Upon the face of the sheet the display matter is depicted by a suitable paint, care being taken that the interstices are not filled up by the paint. The rear side of the sheet is then given a required coat of varnish until the 80 interstices 7 (see Fig. 5) are entirely filled. The display matter for the rear of the sheet is then painted upon the rear of the said sheet.

When the sheet is illuminated from the 85 front, only the matter depicted upon the face thereof will be visible from the front of the sign, but when the rear of the sheet is illuminated, only the matter depicted upon the rear thereof will be visible from the 90 front of the sign.

Electric bulbs 8 of the elongated type illuminate the front of the sheet.

Electric bulbs 10 within the casing are adapted to illuminate the sheet 1 from the 95 rear. The wires 11 from an electric circuit are led into the casing through a hole 13 and are connected to an electric flasher 14 which may be of ordinary construction.

The flasher alternately switches the current from the bulbs 8 to the bulbs 10 and from the bulbs 10 to the bulbs 8.

Instead of the lights from the bulbs 8 being intermittent they may be constant; in that case the bulbs 10 would alone be intermittent, but the light from them would be of greater magnitude so as to overpower the lights from the bulbs 8. Similarly the bulbs

8 may be intermittent and the bulbs 10 constant.

What I claim is:—

1. An intermittently illuminated sign having an interstitial screen at the front thereof and bearing a design on the face thereof, transparent filling material applied to the interstitial screen and bearing a design which will appear through the interstices 10 when the screen is illuminated from the rear, substantially as set forth.
2. An intermittently illuminated sign having an interstitial screen at the front thereof and bearing a design on the face thereof, varnish applied to the interstitial screen and bearing a design thereon which will appear through the interstices when the screen is illuminated from the rear, substantially as set forth.
3. In an illuminated sign, the combination 20 with a casing and electrical intermittent illumination of an interstitial screen, a design on the face thereof and transparent filling material applied to the interstitial screen and bearing a design which will appear through the interstices when the screen is illuminated from the rear substantially as set forth.
4. In an intermittently illuminated sign, 30 an interstitial screen at the front thereof, a design on the face thereof, the interstices of said screen being filled with varnish from the rear side thereof, a design painted on the varnish filling the interstices which design 35 will appear through the interstices when the

screen is illuminated from the rear, substantially as set forth.

5. In an intermittently illuminated sign, an interstitial screen of wire gauze at the front thereof, a design on the face of said screen, the interstices of said wire gauze screen being filled with varnish from the rear side thereof, a design painted on the varnish filling the interstices which design will appear through the interstices when the screen is illuminated from the rear, substantially as set forth.

6. An illuminated sign comprising a casing, an open front to said casing, a recess within said casing, a slot in the top of said casing leading to said recess, a frame retained in position in the recess and adapted to be inserted through said slot, a sheet of interstitial material stretched upon said frame, a design depicted on the face of said sheet, transparent filling material applied to the interstices of said sheet, display matter depicted upon the rear side of said sheet, said sheet being alternately illuminated from the front and rear, substantially as set forth.

In testimony whereof I have signed my name to this specification in the presence of two subscribing witnesses:

WILLIAM REED-LETHBRIDGE.
